DESIGN FOR A SPECTACLE FRAME

Vincent Tanasso, Harrison, N. Y.

Application November 13, 1947, Serial No. 142,513

Term of patent 7 years

(Cl. D57—1)

To all whom it may concern:

Be it known that I, Vincent Tanasso, a citizen of the United States, residing in Harrison, in the county of Westchester, State of New York, have invented a new, original, and ornamental Design for a Spectacle Frame, of which the following is a specification, reference being had to the accompanying drawing, forming a part thereof.

In the drawing:

Figure 1 is a front elevation of a spectacle frame showing my new design.

Figure 2 is a side elevation thereof;

Figure 3 is a top plan view of the same, the temples being shown fragmentarily for convenience of illustration, and

Figure 4 is a rear view.

I claim:

The ornamental design for a spectacle frame, as shown and described.

VINCENT TANASSO.
